UNITED STATES PATENT OFFICE.

GEORGE ALBERT TUCK, OF SAN FRANCISCO, CALIFORNIA.

AIR HEATER AND VENTILATOR.

1,406,111.

Specification of Letters Patent. Patented Feb. 7, 1922.

Application filed July 21, 1921. Serial No. 486,501.

To all whom it may concern:

Be it known that I, GEORGE ALBERT TUCK, a citizen of the United States, residing at San Francisco, in the county of San Francisco and State of California, have invented certain new and useful Improvements in Air Heaters and Ventilators; and I do declare the following to be a full, clear, and exact description of the invention, such as will enable others skilled in the art to which it appertains to make and use the same.

This invention relates to an improved heater and ventilator and one object of the invention is to provide an improved heater by means of which air may be heated in a very efficient manner and the heated air passed into a distributing pipe.

Another object of the invention is to provide a heater having an improved heat radiating section positioned in a casing, the radiator being so constructed that air may pass through the radiator and around the same when passing from the air inlet to the air outlet of the heater casing.

Another object of the invention is to provide an improved heater having the radiator structure mounted above the burner and so constructed that the products of combustion from the burner may pass through the radiator to thoroughly heat the same and then pass out through the outlet neck of a hood at the upper end of the radiator structure.

Another object of the invention is to provide a heater so constructed that the air may be drawn into the upper end of the heater casing by means of an electric fan and by this fan forced down through and about the radiator and out through an outlet at the base of the casing thus causing the air to leave the heater at the point of greatest heat.

Another object of the invention is to provide a radiator construction formed of sections so connected that they may be easily put together and when together have joints which will be air-tight and thus prevent the products of combustion from mixing with the air.

Another object of the invention is to provide a heater having a gas burner provided with a valve and operating means for opening the valve when the electric fan which draws air into the heater is turned on.

Another object of the invention is to so

construct the valve operating means that the means for imparting movement to the same to open the valve may consist of arms pivotally mounted about a disk carried by the shaft of the fan and moved outwardly by centrifugal force against the action of springs when the fan is turned on.

This invention is illustrated in the accompanying drawings, wherein:

Figure 1 is a view showing the improved heater in vertical section. 65

Figure 2 is an enlarged vertical sectional view through one of the radiator sections and a portion of another.

Figure 3 is a view showing one of the radiator sections in top plan. 70

Figure 4 is a transverse sectional view through the hood of the heater.

Figure 5 is a transverse sectional view through the lower portion of the heater.

Figure 6 is a vertical sectional view 75 through an upper section of the heater.

Figure 7 is a transverse sectional view through the heater section shown in Fig. 6.

Figure 8 is an enlarged view showing the fan and valve operating means carried 80 thereby in side elevation.

Figure 9 is a vertical sectional view through the structure of Fig. 8 looking towards the motor of the fan.

Figure 10 is a vertical sectional view 85 taken along the line 10-10 of Fig. 8 with the pivoted arms in a retracted position.

Figure 11 is a view similar to Fig. 10 showing the pivoted arms extended by centrifugal force. 90

Figure 12 is a perspective view of one of the pivoted arms.

This improved heater is provided with a casing 1 which is positioned vertically and is provided with an inlet 2 at its upper end through which air may enter the casing 1 and with an outlet 3 adjacent its lower end through which air may pass out of the casing. The base 4 of this casing 1 carries a gas burner 5 which is supplied with gas by means of a pipe 6 controlled through the medium of a valve 7 which is normally closed and will be opened by having its valve stem drawn upwardly through the medium of a rod 8 which extends upwardly 95 through the outlet 3 and into the inlet 2. 100

A pilot burner 9 is provided in operative relation to the burner 5 so that when the

valve 7 is opened and the gas flows through the pipe 6 to the burner 5 the gas will be ignited.

The air heater is provided with a supporting base 10 which is positioned in the casing 1 above the burner 5 and is provided with an air inlet 11 so that the proper amount of air may be supplied for good combustion and to create the proper draft.

10 This supporting base 10 is tubular and is open at its lower end and at its upper end is provided with a cross bar 12 which extends across the open upper end of the base and thus provides spaced outlets through 15 which the products of combustion will pass.

The radiator which is positioned between the base 10 and hood 13 is provided with upper and lower sections 14 and 15 which are of substantially a duplicate construction and intermediate sections 16 which will have a duplicate construction and any number of which may be provided according to the size of the heater to be constructed. Rods 17 extend from the base 10 up through

25 the sections which form the radiator and have their upper end portions extending above the hood 13 to carry a cast iron ring 18 upon which a fan 19 is mounted. Each of the sections 14 and 15 is provided with 30 an outer circular wall 20 and an inner circular wall 21 thus providing space between the two walls as shown in Fig. 7. The central passage 22 within the wall or sleeve 21 is closed at one end and passageways 23

35 lead from the sleeve 21 through the outer wall or sleeve 20 thus providing transversely extending passages with which the central passage 22 communicates. From an inspection of Fig. 7, it will be further noted

40 that passages 24 for products of combustion are provided upon opposite sides of the transversely extending air passage so that the products of combustion may pass from the tubular base or support 10 through

45 these passages 24 into the intermediate sections of the radiator and after passing through the intermediate sections of the radiator, the products of combustion may pass through the passages 24 of the upper 50 section 14 into the hood 13 through which they will pass over the baffle 25 and out through the outlet passageways 26 into a pipe 27 which communicates with the chimney 28.

55 Each of the intermediate radiator sections 16 is provided with an inner sleeve or wall 29 and an outer sleeve or wall 30 which is held in spaced relation about the inner sleeve by spacing bars 31. In addition to holding the sleeves 29 and 30 in spaced relation, the rods 31 serve as heat conductors since they will be thoroughly heated by the products of combustion passing between the sleeves and this heat will be passed to the sleeves and fins 32 carried by the outer

sleeve. The inner sleeves or walls 29 provide a passage leading from the central passage 22 of the upper section 14 to the central passage 22 of the lower section 15 and the space between the walls 29 and 30 provides an annular passage communicating at its upper end with the passages 24 of the upper section 14 and at its lower end with the passages 24 of the lower section 15. It will thus be seen that air entering the casing 1 through the inlet 2 at the upper end of the casing may pass down through this casing and out through the outlet 3, a portion of the air while passing downwardly passing into the passageways 23 of the upper section 14 of the radiator and then passing downwardly through the intermediate radiator sections 16 and out through the passageways 23 of the lower section 15. The air will thus be heated both by contact with the walls of the central passage and by contact with the outer walls of the radiator and fins 32 carried thereby. In order to prevent the products of combustion from escaping while passing from the base 10 to the hood 13, the sections 14, 15 and 16 have been provided with annular ribs or rings which fit in overlapping relation as shown in Figs. 1 and 2 when the sections are put together. It will thus be seen that when cement is applied to the ends of the sections 14, 15 and 16 and these sections placed one upon the other, air-tight joints will be formed between the sections and the products of combustion will be prevented from leaking through the joints of the sections and mixing with the air in the casing.

In order to open the valve 7 when the fan is turned on, there has been provided means operated from the fan and specifically illustrated in Figs. 8 to 11. Referring to these figures, it will be seen that the upper end portion of the rod 8 extends above the fan shaft 33 and has its upper end passing through a guide 34 carried by a plate 35 which is connected with the fan housing by bolts or rods 36. A cross arm or plate 37 is provided intermediate the fan shaft 33 and guide 34 and is provided with upper and lower abutment flanges 38 and 39 which are arcuate as shown in Fig. 9. Leaf springs 40 are positioned as shown in this figure and have their outer ends seated in notches formed in the block 41 carried at the outer ends of the side arms 42 of the plate 35. The inner ends of the leaf springs 40 are seated in notches formed in a socket block 41' carried by the rod 8 above the upper flange 38 and it will thus be seen that these springs tend to assist in retaining the rod in an adjusted position. The valve which, as previously stated is of a conventional construction, is normally held in a closed position and in order to move the valve to an 130

open position, it is necessary to draw the rod 8 upwardly against the action of spring means holding the valve closed. It is further desired to have the valve move to an open position when the fan is turned on and in order to do so, there has been provided rod actuating means which will now be described.

A circular disk or plate 43 is mounted upon the fan shaft 33 and is connected with the hub 44 of the fan by rods 45 so that when the fan is rotating, the disk 43 will also rotate. Arms are pivotally connected with the disk 43 and each is provided with an inner section 46, an intermediate section 47, and an outer section 48. The inner section 46 is pivotally connected with the disk 43 and provided with a side lug 49 which is engaged by a spring 50 so that normally, the arms will be retained in the position shown in Fig. 10 with the free end portion of the intermediate section of an arm extending in overlapping relation to the inner section of an adjoining arm. It will be further noted that when in this position, the curved end faces 51 of the outer sections 48 will engage the upper face of the flange 39 and thus the flange 38 extends across the outer edge faces of the intermediate and outer sections 47 and 48. When the fan is turned on, the centrifugal force exerted, will cause the arms to swing outwardly to the position shown in Fig. 11 and as the arms swing outwardly, the outer edge faces of the sections 47 and 48 will engage the underface of the outstanding flange 38 and will thus tend to move the rod 8 upwardly to open the valve 7. The gas will flow through the pipe 6 and be ignited by the pilot 9 and the air which is driven downwardly through the casing will be heated as previously explained and pass out through the outlet 3. When the rod 8 is moved upwardly, the springs 40 are carried upwardly with it and will assist in retaining the rod in a raised position. When the fan is turned off the springs 50 will tend to return the arms to the position of Fig. 10 and the rod will be moved downwardly as the valve closes. It will thus be seen that with this construction, the shaft will be automatically turned on when the fan is turned on and further that since the valve is opened by the action of centrifugal force, the valve 7 will be partially opened or entirely opened according to the speed at which the fan is rotating. Therefore, the proper amount of heat will always be supplied according to the speed at which air is being forced through the casing. It will be further noted that since the air enters the casing at the upper end and moves downwardly around and through the heater and then passes out at the lower end of the casing the air will be heated to a greater extent as it moves toward the outlet and will leave the casing at

the point of greatest heat. It will be further noted that if desired, the gas of the pilot can be shut off and the gas for the burner 5 shut off either by means of the valve 52 or by means of a separate valve 70 placed in the gas-line in advance of the valve 7. The device can thus be used as a ventilator for supplying fresh air or cooled air from a suitable source of cool air and this fresh air passed through the casing and 75 through the outlet 3 into the pipe which is to distribute the fresh air or hot air through a building. By having the casing provided with a removable cover 53, the cover can be removed and easy access had to the fan for 80 making repairs. There has thus been provided a device for use in supplying hot or fresh air to a building and there has further been provided a device in which the air can be heated in a very effective manner 85 and further the burner provided with a flow of gas which will be increased accordingly, to the speed at which the fan rotates. Therefore, the air will always be heated at the right temperature and without danger of 90 waste of gas.

I claim:

1. A heater comprising a casing having an air inlet and an air outlet, a burner in the casing, a heater in said casing and having a hollow base above the burner, a hood in the upper portion of the casing having an outlet extending through said casing, and a radiator element between the base and hood and having superimposed sections having inner and outer sleeves forming a central air passage and a products of combustion passage about the air passage and between the sleeves, the products of combustion passage having communication with the 100 base and hood and the air passage being closed at its ends and adjacent the ends having necks extending through the outer sleeve.

2. A heater comprising a casing having an 110 air inlet and an air outlet, a source of heat in the casing, a radiator in the casing having a hollow base above the source of heat, a hood in the casing having an outlet extending through the casing, and an intermediate 115 section between the base and hood having a central air passage and a products of combustion passage about the air passage, the products of combustion passage having communication with the base and hood and the 120 air passage being closed at its ends and having passageways extending through the products of combustion passage and communicating with the interior of the casing.

3. In a heater, a heat absorbing and radiating structure comprising a hollow open ended base, a hood having an outlet, and a structure between said hood and base having an outer sleeve and an inner sleeve extending through the outer sleeve and form- 125 130

ing a central passage and a passage between the inner and outer sleeves, the inner sleeve being closed at its ends and adjacent the ends being provided with passageways forming side pipes extending from the central passage through the outer sleeves.

4. A heater comprising a casing having an air inlet and an air outlet, a source of heat in the casing, a heater mounted in said casing and having a hollow base above the source of heat, a hood in the upper portion of said casing having an outlet extending through the casing, and a radiator element between the base and hood and having intermediate and end sections each having spaced inner and outer sleeves to provide an air conduit of the inner sleeve and a products of combustion passage between the inner and outer sleeves, the end sections having the inner sleeves closed at their outer ends and provided with neck extensions extending through the sides of the outer sleeves and communicating with the interior of the casing.

25. 5. The structure of claim 4 having the contacting ends of the radiator sections provided with annular ribs overlapping when the sections are placed one upon another and providing air-tight joints when the sections are 30 cemented together.

6. A heater comprising a casing having an air inlet and an air outlet, a burner in the casing, a tubular support above said burner open at its upper and lower ends and 35 provided with an air inlet extending through the casing, a heater resting upon said support and having a lower section provided with a transverse air passage and a central passage extending vertically from the 40 transverse passage through the upper end of the lower section and about the vertical passage provided with products of combustion passages communicating with the interior of said support, intermediate sections supported by the lower section and each having a central air passage and a circumferentially extending products of 45 combustion passage about the air passage, an upper section provided with a pocket 50 registering with the air passage and passages about the pocket registering with the products of combustion passages, and further having transverse passages leading from the pocket through the sides of the 55 upper section, and a hood upon the upper section having an outlet leading from one side and a baffle plate vertically and across the outlet.

7. A heater comprising a casing having 60 an air inlet adjacent its upper end and an air outlet adjacent its lower end, a burner in the casing below the air outlet, and a heater in the casing, said heater comprising a tubular open ended base mounted above 65 the burner having an air inlet extending

from its lower end through the casing, a radiator disposed vertically in said casing and having upper and lower sections and intermediate sections between the upper and lower sections, and a hood carried by the 70 upper section and having an outlet for products of combustion passing through the casing, the intermediate sections each having spaced inner and outer sleeves providing a central air passage and an annular passage between the sleeves for products of combustion and the upper and lower sections each having a transverse air passage and a vertical air passage leading from the transverse passage and communicating with the 75 central air passage of an adjoining intermediate section and further provided with vertical products of combustion passages about the central air passage for conducting products of combustion from the base into 80 the passage between the sleeves of the intermediate sections and into said hood.

8. A heater comprising a casing having an air inlet and an air outlet, a source of heat in said casing, a heat absorbing and 90 radiating element, a supply for the source of heat including a control element, a rotary fan for moving air through said casing, and means actuated from the fan when the fan is in motion for actuating said control element and increasing and decreasing the amount of heat according to the speed at which the fan rotates.

9. The structure of claim 8 having the means for actuating the control element including an element carried by the fan and moved by centrifugal force created when the fan is in motion.

10. A heater comprising a casing having an air inlet and an air outlet, a fluid burner 105 in said casing, a heat absorbing and radiating element in said casing, a fuel conductor pipe for said burner having a control valve, a rotary fan for moving air through the casing, and means operated from the fan 110 for opening the valve when the fan is in motion.

11. A heater comprising a casing having an air inlet and an air outlet, a fluid burner in said casing, a heat conducting and radiating element in said casing above said burner, a fuel pipe leading to said burner and having a normally closed valve provided with a stem movable to open the valve, a rod extending upwardly from the stem of the valve, a rotary fan at the air inlet of said casing, and means actuated by said fan for moving the rod to open the valve when the fan is turned on.

12. The structure of claim 10 having the 125 rod moving means moved by centrifugal force set up when the fan is rotating and the rod moved to open the valve according to the speed at which the fan rotates.

13. A heater comprising a casing having 130

- an upper air inlet and a lower air outlet, a burner in said casing, a heat conducting and radiating element in said casing above said burner, a pipe leading to said burner and 5 having a normally closed valve provided with a stem moved to open the valve, a rod extending upwardly from the stem of the valve adjacent said casing, a rotary fan at the air inlet of said casing, spaced abutments carried by said rod, a disk carried by 10 the shaft of said fan, arms pivotally connected with said disk and extending between the abutments of said rod, and springs yieldably retaining the arms in a retracted position, the arms being thrown outwardly by centrifugal force and engaging one of the abutments to move the rod upwardly and open the valve when the fan is rotating. 14. A heater comprising a casing having 20 an upper air inlet and a lower air outlet, a gas burner in said casing below the air outlet, a heat conducting and radiating element in said casing above said burner, a gas pipe leading to said burner and having a normally closed valve provided with a stem moved upwardly to open the valve, a rod 25 extending upwardly from the stem of the valve adjacent said casing, a rotary fan at the air inlet of said casing, upper and lower abutments carried by said rod, a disk carried by the shaft of said fan, arms pivotally connected with said disk and extending between the abutments of said rod, each arm having an inner section pivoted to the disk, 30 an intermediate section extending transversely from the inner section and each having its free end portion overlapping the inner section of an adjoining arm when the arms are in a retracted position, and an outer section upon the intermediate section and terminating short of the free end thereof for engaging the lower abutment when the arms are in a retracted position, and springs connected with the disk and inner 35 sections of the arms to yieldably retain the arms in a retracted position, the arms being thrown outwardly against the action of the springs by centrifugal force and engaging 40 sections of the arms to yieldably retain the arms in a retracted position, the arms being thrown outwardly against the action of the springs by centrifugal force and engaging 45 the upper abutment to move the rod upwardly and open the valve when the fan is rotating.
15. In a heater, a casing having an inlet and an outlet, a rotary fan for passing air through the casing, a source of heat, a supply control element having an operating element extending to a point adjacent the fan and having spaced abutment elements, a disk carried by the shaft of the rotary fan, arms pivotally connected with the disk and extending between said abutments and 60 springs yieldably holding the arms in a retracted position, the arms being thrown outwardly by centrifugal force and engaging one of the abutments to move the operating element when the fan is rotating. 65
16. In a heater, a casing having an inlet and an outlet, a rotary fan for passing air through the casing, a source of heat, a supply control element having an operating element extending to a point adjacent the fan and having spaced abutment elements, a disk carried by the shaft of the rotary fan, arms pivotally connected with the disk and extending between said abutments, each arm having an inner section pivoted to the disk, 70 an intermediate section extending transversely from the inner section and each having its free end portion overlapping the inner section of an adjoining arm when the arms are in a retracted position, and an outer section upon the intermediate section and terminating short of the free end thereof for engaging the lower abutment when the arms are in a retracted position, and springs connected with the disk and inner 75 sections of the arms to yieldably retain the arms in a retracted position, the arms being thrown outwardly against the action of the springs by centrifugal force and engaging the upper abutment to move the rod upwardly and open the valve when the fan is rotating. 80
17. In testimony whereof I have hereunto set my hand.

GEORGE ALBERT TUCK.
